UNITED STATES PATENT OFFICE.

JOSEPH E. LEMYRE, OF MANCHESTER, NEW HAMPSHIRE.

LASTING-HAMMER.

SPECIFICATION forming part of Letters Patent No. 594,997, dated December 7, 1897.

Application filed March 29, 1897. Serial No. 629,718. (No model.)

To all whom it may concern:

Be it known that I, JOSEPH E. LEMYRE, a citizen of the United States, residing at Manchester, in the county of Hillsborough and State of New Hampshire, have invented certain new and useful Improvements in Lasting-Hammers; and I do hereby declare the following to be a full, clear, and exact description of the invention, such as will enable others skilled in the art to which it app pertains to make and use the same.

It is a common practice among lasters to place a quantity of tacks in their mouths before commencing to last a shoe or boot, extracting them one at a time as required during the operation. This practice is not only dangerous to health, but is dangerous to life. Still the practice grows and increases for the reason that time can be saved, and hence a day's wages made larger than if a laster should take his tacks from a suitable receptacle near at hand.

The object of the present invention is to provide a substitute for one's mouth as a receptacle for tacks which shall make it possible for a laster to accomplish his work still more rapidly.

The invention consists in a receptacle for tacks which may be attached to either a hammer or a pair of pliers, and to certain novel mechanism whereby the tacks contained in said receptacle are fed and stuck one at a time where desired, ready to be struck by a hand-hammer, as fully set forth in the following specification and claims and clearly illustrated in the drawings, forming a part thereof, of which—

Figure 1 is an elevation showing one of my improved tack-reservoirs as applied to a laster's hammer, Figs. 2, 3, and 4 being details. Fig. 5 is a broken elevation showing that side of my improved laster's hammer opposite to that shown in Fig. 1. Fig. 6 is an end view of the tack-reservoir with its feeding mechanism, the hammer being shown with a portion of its handle in dotted lines.

Similar reference-letters designate corresponding parts in all the views.

A represents a hammer-head, and B is its handle, to which my improved tack-reservoir may be attached. This tack receptacle or

reservoir has two compartments, a large one C and a smaller one C', by reason of a partition c, which has an opening c' at its bottom, thus limiting the quantity of tacks which may enter the compartment C', which serves the purpose of a feed-chamber for the tacks. The outer side of this feed-chamber extends below the bottom thereof and is provided with a vertically-elongated opening c², and said bottom has a narrow opening c³ extending its entire length adjacent to the outer side of said chamber, and a suitable carrier D, having in its top a deep slot d, is fitted to said opening c³ and permitted a limited vertical movement 65 therein by means of a screw d', which passes through one end of a lever D' and the opening c² of the feed-chamber C' and is threaded to the lower part of said carrier D, the opposite end of said lever D' being rigidly mounted 70 at one end of a shaft E, carried in bearings e e, provided upon the tack-race, to be hereinafter explained, the opposite end of said shaft being fitted with a crank e', connected with a trigger or lever F (held normally in 75 the position shown by a suitable spring f') by the connecting-rod f, as seen in Figs. 1, 5, and 6.

The normal position of the carrier D is best shown in Fig. 4—i. e., when the top in which 80 the slot d is formed shall be flush with or slightly below the bottom of the feed-chamber C'. Hence some of the tacks which enter said feed-chamber through the opening c' fall into the slot of said carrier with their 85 heads resting upon the top thereof.

In the drawings the lever or trigger F is shown in its normal position, and the movement of the parts just described is one of the functions of said lever, and by moving said 90 lever (referring to Fig. 1) to the left the carrier rises to a point opposite the openings c⁴, formed in the end walls of the feed-chamber, (one of which openings is shown in Fig. 4,) and by tipping the hammer in either direction, as would naturally follow its use, the tacks in said carrier chase each other out through either of said openings c⁴ into either of the spirally-inclined tack-races G G', whence said tacks unite in the horizontal 100 curved race H, leading to the striking mechanism soon to be described, the opening h,

formed in the side of the race H, admitting the tacks from the spiral race G', as seen in Figs. 2 and 3.

All three of the tack-races may be supplied 5 with strips of metal arranged a little above their upper edges to prevent the accidental displacement of the tacks while they are moving through said raceways, as shown at g'g'h', and to guard against clogging a spring-actuated feed-dog I (shown best in Figs. 2 and 5) is pivotally attached to one end of a lever i, the opposite end of which is secured to an ear g², attached to or formed upon the race G, as best shown in Figs. 1 and 2, and secured 10 to said lever i is an arm i', the free end of which is provided with a lateral projection i², which engages the lever F at a certain point in its stroke, whereby the lever i is moved upward and backward, thus disengaging the 15 feed-dog I from the tacks in the raceway H, so that when said dog again drops to its normal position it will engage tacks back of those which it had just left, and so the movement continues with each movement of the trigger 20 or lever F, the spring i³ serving two purposes—viz., to insure contact with the tacks and to draw the tacks in the raceway H forward and thus keep them moving toward the tack-sticking mechanism at the end of said raceway H.

In Figs. 2 and 3 I show this tack-driving mechanism in detail. The raceway H terminates at one side of a vertical case or tube J, which contains the tack-driver K, the upper 25 end of which is connected to a spring-arm k, serving to normally hold it down within its case or tube, which has a vertical opening j in its side at the proper point to connect with and receive tacks from said raceway H. Opposite this opening j in said tube J are provided 30 a tack-separator L and a feed-bar M, both working at right angles to the raceway H, the separator being ahead of the feed-bar, as shown.

45 S represents the tacks, several of which are shown by dotted lines in Fig. 3, and in Fig. 2 one tack is shown in solid black, the separator L having moved outward, separating this particular tack from the others and placing it directly in front of the feed-bar M, which will now move sufficiently to push said tack through the opening j of the case or tube J and under the spring-actuated tack-driver K, which immediately snaps down upon said 50 tack with enough force to leave it standing ready to be struck by the hammer A.

The upper end of the trigger or lever F is rigidly secured to a shaft f', carrying at its opposite end a crank O, which is connected 60 by the bar p to the lower end of a rocker or lever P, hung on a pin or screw p', the upper end of said lever P engaging a bell-crank Q, by which the spring-arm k is raised, as shown best in Fig. 5. The lever P is also connected 65 to the bell-crank R by the connecting-bar T. This bell-crank R operates the separator L and feed-bar M, one before the other, as

shown best in Fig. 5, one end of the crank bearing against the separator, while a projection r, formed upon one side of said crank 70 and near the end which contacts with the separator, engages the feed-bar M, said projection r being located the proper distance from the end of said bell-crank to cause the separator to move before the feed-bar. The tack-driver 75 K rises just before the feed-bar M pushes a tack under it, when it snaps down upon the tack, the operation being repeated with each movement of the trigger or lever F.

It is advisable to provide some means to prevent the tacks in the raceway H from moving in a direction away from the tack-sticking mechanism, and, while the dog I is designed to effect this, if desired, a separate spring-actuated stop may be provided for the 85 purpose.

A spring N bears upon the separator L and feed-arm M in a manner to hold them in such position as will leave the tacks a free passage from the raceway H to the tube J and to return them to their normal position directly after being moved by the bell-crank R and its projection r.

Having described my invention, what I claim is—

1. In a device of the character described, a suitable receptacle for tacks, raceways leading from each end of said receptacle to a point of union, one with the other, and means whereby said tacks may be dropped consecutively 100 with their heads up and then struck, substantially as set forth.

2. The combination with a tack-receptacle, of a tube, a raceway leading from the receptacle to the tube, a carrier within the receptacle, means for feeding the tacks singly to the tube, a spring-actuated spindle within the tube, and means for simultaneously operating the feeding mechanism, moving the spindle against the spring, and operating the 105 carrier, substantially as set forth.

3. The combination with a tack-receptacle, of a tube, a spring-actuated spindle therein, a raceway leading from the receptacle to the tube, a separator and a feeding-bar for feeding the tacks singly to the tube, a feeding-dog for feeding the tacks along the raceway, and means for simultaneously moving the spindle against the spring and for operating the separator, the feeding-bar, and the feeding-dog, substantially as set forth.

4. The combination with a tack-receptacle, of a tube, a spring-actuated spindle therein, raceways communicating with the opposite sides of the receptacle and with the tube, a 125 carrier within the receptacle between the ends of the raceways, a separator, a feed-bar, and means for simultaneously moving the spindle against the spring and operating the separator, the feed-bar, and the carrier, substantially as set forth.

5. The combination with a tack-receptacle, of a tube, a spring-actuated spindle therein, a raceway leading from the receptacle to the

tube, a separator, and a feed-bar, a bell-crank lever, provided with a shoulder for engaging with the feed-bar, and means for simultaneously moving the spindle against the spring and operating the lever, substantially as set forth.

6. The combination with a tack-receptacle, of a tube, a spindle therein, a spring connected with the spindle, a bell-crank lever engaging with the intermediate portion of the spring, and means for feeding tacks to the tube, and a trigger provided with means for simultaneously operating said mechanism, and for operating the lever, substantially as set forth.

15 7. The combination with a tack-receptacle provided with exits and a slotted extension,

of a tack-driver, a raceway leading from each of the openings to the driver, a carrier within the receptacle, the upper end of which is provided with means for delivering tacks to the opening and the lower end is adjacent to the slotted extension, means for feeding the tacks singly to the driver, and a lever provided with means for engaging with the carrier at the slot of the extension and for operating the feeding mechanism and the driver, substantially as set forth.

In testimony whereof I affix my signature in presence of two witnesses.
